INLAID LINOLEUM AND PROCESS OF PRODUCING SAME

Application filed July 28, 1928. Serial No. 295,861.

Our invention relates to a linoleum, particularly a floor covering, and process of producing the same.

Our main object is to provide an improved inlaid linoleum which has the mortar-representing or tesserae-separating portions somewhat sunk below the level of the exposed faces of the tesserae, and which shall more nearly simulate the appearance of hand-laid work.

Heretofore, linoleum had been produced with a pattern representing tiles or bricks for example with intervening differently-colored material representing the mortar joints, and the tiles or other tesserae have been made to stand out in relief by indenting the mortar-representing portions by means of ribs located on the under face of a suitable press. This method results in a product which is unsatisfactory in various particulars. For one reason, as the indenting ribs are of the same shape or cross-section throughout their length, the indentation is entirely regular, contrary to what it is in ordinary hand-laid ceramic tile floor. Also difficulty is often experienced in getting the indentation accurately to match with the mortar-representing material, with the result that the indentation is "off" a considerable amount, perhaps sufficient to cause the product to be rejected, and at least requiring frequent adjustment and reregistration of the material with reference to the ribs on the press. Also, in the case of indenting the mortar-representing portions of so-called "straight line" inlay material, the pressure may cause a breaking away between the adjoining edge of the tesserae and mortar-joint-representing material.

Our invention obviates all those objections and by it may be produced a floor or other covering which more accurately simulates the irregular appearance of hand-inlaid ceramic tiling.

We are aware that various departures from the specific steps or the particular embodiment hereafter described may be made. In the drawings, we have shown, merely as an illustrative example, parts of a linoleum

sheet as may be made according to our invention.

In such drawing,

Figure 1 represents a plan view;

Figure 2 a portion in elevation before pressure is applied, and

Figure 3 a detail, partly in section and partly in perspective, of the resulting product.

In Figure 1, the tesserae 1, 2, 3, 4, etc., such as imitation tiling for example, are arranged in any desired design spaced somewhat from each other by mortar-representing portions 5 of an appearance different from the tiles.

Linoleum is a product of oxidized linseed oil, with other ingredients, usually mounted upon a burlap or other suitable backing. Linoleum has two main uses, as a floor covering and as a wall or ceiling covering. When made for use as a floor covering it usually is comparatively thick and the proportion of oxidized oil to filler (granular cork or wood dust and kauri or other gum, for example) is, in the better grades, comparatively high in order to render the product highly resistant to wear. When adapted for a wall covering it is not subjected to wear in the same degree so the linoleum (such for example as the well-known lincrusta) is usually made relatively thin, and the proportion of the oil to the filler used is usually considerably lower. In Figures 2 and 3, 6 represents the backing and 7 a base of linoleum material which may be formed in any desired manner, for example as ordinary single-colored linoleum is formed, i. e., by compressing the material onto the fabric backing and consolidating it by means of suitable pressure appliance, such as calendering rolls or a hydraulic press. This base sheet should be relatively soft, i. e., sufficiently soft to allow the tesserae to be embedded therein by pressure.

The tesserae may be formed in any suitable manner and of any desired colors or shapes. They may be cut from sheets of previously formed vari-colored linoleum, as the well-known "straight-line" inlays are made. To obtain the best results, they should be uncured, i. e. somewhat soft or malleable.

After having been arranged on the base 7, spaced from each other somewhat as indicated in Fig. 2, suitable pressure is applied to the exposed faces of the tesseræ only, such as in a flat-faced press (not shown) sufficient to force them bodily into and (as it were) surface-weld them to the base material indicated in Figure 3, which will cause the lower-lying intervening mortar-representing material (such as at 20 in Figure 2) to flow relatively upward between the tesseræ as at 8 and 9 in Figure 3. If the pressure is relieved before the tesseræ are completely embedded in the base material, the former will stand somewhat in relief above the mortar-joint-representing material and give the effect of sunken joints i. e., of the tesseræ in relief, but without the press touching such joint material.

The pressure upon the tesseræ will, if the material is sufficiently soft, cause the tesseræ to be materially expanded slightly at their edges and to assume a rounded or somewhat pointed form, as indicated for example at 10, 11 and 12 in Figure 3. This will result in the exposed faces of the tesseræ merging somewhat gradually into the mortar-representing material, as indicated for example at 12 in Figure 3. The downward pressure will of course further consolidate those portions of the base material which are underneath the tesseræ. The lateral expansion of the tesseræ also serves to consolidate further the intervening joint-forming portions and to cause the tesseræ to be surface-welded to and in some cases interlocked with them as indicated. Of course, these shapes will not be entirely regular due to minute variations in pressure or consistency of the tesseræ material. This results in the mortar-representing spaces being not of the same width throughout the pattern, due to the unequal lateral expansion of the tesseræ and relatively upward flow of the mortar-representing material between them. In fact regularity is not desired. Slight irregularities of tile-position, tile-outline, joint-width and groove-shape are desired because they more nearly simulate such actual irregularities in hand-laid ceramic tiling. It is more artistic. This is particularly true when the irregularities do not reoccur with regularity such as in successive pattern-repeats. The trade heretofore has evinced a decided preference for linoleum made by the ordinary "straight-line" process—in which the tesseræ are cut out of previously-consolidated sheets and assembled with their edges closely abutting—over inlays made by the "moulded" process because in the latter the unavoidable ragged edges between the inlays look like poor workmanship, and the raggedness occurs all around each inlay. Various expedients have been tried to hide or minimize this ragged-edge appearance and more clearly to simulate "straight-line" effects in goods made by the moulded

process, but such attempts have not been successful. The raggedness is still apparent. The "straight-line" edge, whether or not actually straight, is preferred because it is clearly defined and so more like ceramic tiling.

A further advantage in what might be termed "irregular irregularities" is obtained in our product and is caused by placing the tesseræ in spaced relation on the base sheet, parts of which will be squeezed up between the tesseræ to represent the intervening mortar joints. Whether this locating of the tesseræ is done by hand or by automatic inlay-positioning machines, there will necessarily occur slight irregularities in location of the tesseræ, but as there is a considerable space between them it matters not that a tile is placed somewhat askew (see tile 2 of Fig. 1) as may occur even in machine-laid tesseræ. This would be a defect in an ordinary "straight-line" inlay in which the inlays must be placed with the edges of the inlays closely abutting each other. The unavoidable inaccuracies of hand or machine inlaying are converted into desirable artistic results. Also the unavoidable slight differences in softness of the tesseræ may cause some of them to expand somewhat more than others. In our product the result is a desired irregular irregularity of joint width, automatically obtained.

For example, in Figure 1 the width of the space between the tesseræ 2 and 4 is somewhat wider than that between 1 and 4 or between tesseræ 13 and 14. This more nearly simulates the actual appearance of hand-laid ceramic tiling and avoids the relatively hard and uniform and so unnatural appearance of indented-joint linoleum heretofore produced. Also when the ordinary "straight-line" inlaid, smooth-surfaced linoleum is by ribs indented along the joints, the somewhat shearing effect of the ribs often opens the vertical joints between inlays, resulting in a defective product which must be discarded or sold at a less price as a "second". Even if the joint is not actually opened at that time, it may be so weakened that the joint will split open when a roll of goods is opened out for laying, or after being laid, which is worse. Our product in its form illustrated needs no actual indentation of the material and avoids this step. Also the sunken joint or sunken strip between tesseræ is always exactly where it ought to be. A further advantage is that the mortar-representing joints between tesseræ may be made considerably narrower than would be commercially possible in either the ordinary moulded or straight-line processes.

The pressure upon the tesseræ exerted by the press also may be sufficient to cause the joint-filling material, whether in the form of a sheet into which the tesseræ are bodily embedded or otherwise introduced between the tesseræ, to flow relatively upward even above

the rounded nose of the expanded tesserae, as indicated at 10 in Figure 2 or at 11, so that these edges of the tesserae are actually embedded laterally into and interlocked with the intervening base material. This results in an extremely solid product, as the edges are in effect mechanically interlocked with the interposed material. Of course, all of the edges of the tesserae will not necessarily be so interlocked in all cases.

Our product, when produced as above described, results in an inlaid linoleum more closely simulating the appearance of actual hand-laid tiling in that it has various irregular irregularities usual in such a product and yet has the relatively clear-cut line of definition between the edges of the tesserae and the mortar-representing portions which is a characteristic of the "straight line" inlay.

We are aware that various modifications may be made in the steps of the process as above described and in the resulting product, without departing from the scope of the invention as claimed. We, therefore, do not limit ourselves to the illustrative example above described.

What we claim is:

1. The process of producing inlaid linoleum which comprises taking previously consolidated linoleum tesserae which are still malleable and arranging them in spaced relation in a desired pattern upon a sheet of somewhat consolidated but still soft linoleum, exerting pressure upon the exposed faces of the tesserae sufficient to embed them in and consolidate them with the base material and simultaneously laterally expand them, and relieving the pressure before the tesserae are completely embedded, thereby producing a sheet having somewhat deformed tesserae with intervening sunken spaces in which the base material is exposed to view.

2. The process of producing inlaid linoleum which comprises cutting out tesserae from sheets of previously consolidated linoleum of the desired colors and arranging them while still malleable in spaced relation in a desired pattern upon a sheet of somewhat consolidated but still soft linoleum, exerting pressure upon the exposed faces of the tesserae sufficient to embed them in and consolidate them with the base material and simultaneously laterally expand them, and relieving the pressure before the tesserae are completely embedded, thereby producing a sheet having somewhat deformed tesserae with intervening sunken spaces in which the base material is exposed to view.

3. The process of producing inlaid linoleum which consists in arranging, upon a base of relatively soft linoleum, malleable linoleum tesserae separated somewhat from each other, and exerting pressure upon the exposed faces of said tesserae sufficient to force the upper margins of said tesserae into a

downwardly inclined form and the tesserae partially but not wholly into the base material, thereby leaving the intervening material at a somewhat lower level.

4. The process of producing inlaid linoleum, which comprises arranging somewhat separated linoleum tesserae upon a base of relatively soft linoleum, and exerting pressure upon the exposed faces of the tesserae sufficient to cause the base material to flow relatively upward between and around edges of the tesserae, and relieving the pressure before the base material reaches the level of the tesserae faces.

5. The process of producing inlaid linoleum which comprises arranging in a pattern somewhat separated tesserae and intervening material whose exposed face is below that of adjacent tesserae, both said tesserae and filling material being of relatively-soft linoleum, and exerting pressure upon the exposed faces of said tesserae sufficient to expand the tesserae edges laterally and cause the intervening material to flow upwards, and relieving the pressure before the latter reaches the general level of the tesserae faces, whereby a pattern with sunken intervals is produced.

6. Inlaid linoleum comprising a linoleum base with separated linoleum tesserae bodily embedded in and consolidated with the base material, the exposed faces of the tesserae standing somewhat above but gradually merging into the intervening base material.

7. Inlaid linoleum comprising tesserae spaced somewhat and only partially inlaid into a mortar-joint-representing linoleum material and having margins downwardly inclined and bodily interlocked laterally into the intervening base material.

8. An inlaid linoleum sheet comprising separated linoleum tesserae having substantially "straight-line" edges arranged in a desired pattern on and embedded only partially into, but consolidated with, a base sheet of linoleum, the intervening lower-lying base material being exposed to view.

9. The method of making linoleum simulating tiling, which comprises forming a foundation layer of linoleum composition of substantial thickness and homogeneity extending continuously throughout the area of the intended product; forming separate inlays of linoleum composition, each simulating a tile; preparing the foundation layer and inlays to present plastic surface-portions capable of being welded together and integrated under pressure, and of permitting the inlays to be impressed into the surface of the foundation layer, and of permitting surface-portions of the latter to flow somewhat under pressure; assembling inlays in substantially non-contiguous relationships in imitation of the arrangement of tiling, upon the plastic surface of the foundation layer, so that areas of the latter remain exposed be-

- tween inlays to simulate mortar joints in tiling; applying pressure to impress the inlays into the surface of the foundation layer, and to weld and integrate the two, and to cause part of the foundation layer to flow into spaces between inlays; and governing the pressure of predetermine the relative impressing of the inlays and flowing of the foundation layer, and to dispose the areas 5 of foundation layer between inlays at a lower surface level than that of the inlays, while preserving beneath the inlays collectively a substantially continuous, integral, and homogeneous stratum of the foundation 10 layer material throughout the intended area of the product, whereby said stratum supplies a tough, durable, integral body for the product, independently of the bonds between the inlays and the foundation layer.
10. The method of making linoleum which comprises forming a foundation layer of linoleum composition of substantial thickness and homogeneity extending continuously throughout the area of the intended product, 15 and having plastic surface-portions capable of permitting inlays to be impressed into the surface of the foundation layer, and of permitting surface-portions of the latter to flow somewhat under pressure; assembling inlays 20 in substantially non-contiguous relationships upon the plastic surface of the foundation layer so that areas of the latter remain exposed between inlays; applying pressure to impress the inlays into the surface of the 25 foundation layer, and to cause part of the foundation layer to flow into spaces between inlays; and governing the pressure to predetermine the extent to which the inlays are impressed into the surface of the foundation 30 layer and to produce different surface levels 35 of the inlays and those areas of the foundation layer that intervene between inlays, while preserving beneath the inlays collectively a substantially continuous, integral 40 and homogeneous stratum of the foundation 45 layer material throughout the intended area of the product, whereby said stratum supplies a tough, durable, integral body for the product, independently of the inlays.
11. The method of making linoleum which comprises forming a foundation layer of linoleum composition; forming separate inlays of linoleum composition; preparing the foundation layer and inlays to present plastic 50 surface-portions capable of being welded together and integrated under pressure, and of permitting the inlays to be impressed into the surface of the foundation layer, and of permitting surface-portions of the latter to 55 flow somewhat under pressure; assembling inlays in substantially non-contiguous relationships upon the plastic surface of the foundation layer, so that areas of the latter remain exposed between inlays; applying pressure to impress the inlays into the surface of 60 the foundation layer, and to weld and integrate the two, and to cause part of the foundation layer to flow into spaces between inlays; and governing the pressure to predetermine the relative impressing of the inlays and flowing of the foundation layer, and to dispose the areas of the foundation layer between inlays at a lower surface level than that of the inlays.
12. The method of making linoleum which 70 comprises forming a foundation of linoleum composition of substantial thickness having plastic surface-portions permitting inlays to be impressed into the foundation; assembling inlays in substantially non-contiguous relationships, upon the plastic surface-portions of the foundation; applying pressure to impress the inlays into the foundation and to produce different surface levels of the inlays and such portions of the foundation layer as 75 intervene between inlays, while preserving beneath the inlays collectively a substantially thick stratum of the foundation material 80 which supplies a strong body for the product independently of the inlays.
13. The method of making linoleum which 85 comprises forming a foundation layer of linoleum composition of substantial thickness; and forming inlays; the foundation layer and inlays having surface-portions capable of being welded together and integrated under 90 pressure, and of permitting the inlays to be impressed into the surface of the foundation layer, and permitting surface-portions of the latter to flow somewhat under pressure; assembling inlays in substantially non-contiguous 95 relationships upon the plastic surface of the foundation layer so that areas of the latter remain exposed between inlays; applying pressure to predetermine the relative impressing of the inlays and flowing of the foundation layer, and to dispose at different surface levels the inlays and the areas of foundation layer between inlays, while preserving beneath the inlays collectively a stratum of 100 the foundation layer material which supplies a substantially integral body for the product independently of the inlays.
14. As a new article of manufacture, a linoleum comprising a foundation layer of linoleum composition of substantial thickness and homogeneity extending continuously throughout the area of the linoleum; separate inlays of linoleum composition embedded at least partially in the surface of said foundation layer, and welded and integrated therewith, said inlays being positioned in substantially non-contiguous relationship so 105 that portions of the foundation layer are interposed and exposed between the inlays; the inlays and areas of the foundation layer between inlays being disposed at different surface levels; and the foundation layer having a continuous homogeneous stratum extending integrally beneath the inlays collec- 110
- 115
- 120
- 125
- 130

tively supplying a strong body for the linoleum independently of the bonds between the inlays and the foundation layer.

15. As a new article of manufacture, a linoleum comprising a foundation layer of linoleum composition; inlays embedded at least partially in the surface of said foundation layer, positioned in substantially non-contiguous relationship so that portions of the foundation layer are interposed and exposed between the inlays; the inlays and areas of the foundation layer between inlays being disposed at different surface levels; and the foundation layer having a substantially thick stratum extending beneath the inlays collectively supplying a strong body for the product.

16. As a new article of manufacture, a linoleum comprising a foundation layer of linoleum composition; separate inlays of linoleum composition embedded at least partially in the surface of said foundation layer, and welded and integrated therewith, said inlays being positioned in substantially non-contiguous relationship, so that portions of the foundation layer are interposed and exposed between inlays; the inlays and areas of the foundation layer between inlays being disposed at different surface levels; and the foundation layer having a stratum extending substantially integrally beneath the inlays.

17. As a new article of manufacture, a linoleum comprising a foundation layer of linoleum composition; separate inlays of linoleum composition embedded at least partially in the surface of said foundation layer, and welded and integrated therewith, the inlays being in substantially non-contiguous relationship on the foundation layer, so that portions of the latter are interposed and exposed between inlays; the inlays and the areas of the foundation layer between inlays being located at different surface levels; and the projecting portions of the surface of the product being devoid of abrupt corners.

18. A readily-flexible inlaid sheet comprising flexible tesserae of consolidated but relatively soft material and having straight-line edges spaced slightly from each other and only partially embedded into and surface-welded to an underlying base of similar material, said tesserae being also welded to and standing in relief with respect to integral portions of the base material which extend upwardly between, and the upper surfaces of which are exposed in narrow strips between, said tesserae.

19. The process of producing an inlaid sheet having tesserae in relief which consists in providing a comparatively soft foundation sheet sufficiently thick to allow tesserae to be embedded therein, preparing previously-consolidated tesserae of the desired shapes and colors, arranging said tesserae on the surface of said foundation sheet in the desired

pattern but separated from each other at least such a distance as may be necessary to accomplish the results hereafter specified in this claim, exerting downward pressure upon the exposed faces of said tesserae sufficient to embed them bodily into the base material while at the same time allowing portions of said base material which lie adjacent the tesserae to relatively flow upward between the tesserae, and relieving the pressure before the tesserae are completely embedded, said base material and tesserae material being of such relative consistencies that the pressure exerted upon the tesserae as above described is not sufficient to laterally deform the tesserae enough to close up the spaces between the tesserae or to cause the base material to reach the level of the tesserae faces, whereby there results an inlaid sheet having tesserae in relief with respect to the surface of upwardly-extending portions of the base material which are disposed and exposed to view between the tesserae, the whole forming a substantially integral readily-flexible sheet.

20. The process of producing an inlaid sheet having tesserae in relief, which consists in arranging upon a base of relatively soft material previously-consolidated and shaped tesserae of similar material somewhat spaced from each other, and exerting downward pressure upon the faces of the tesserae sufficient to embed them into the base material and relieving the pressure at such time as leaves sunked areas between the tesserae in which the base material is exposed, whereby, due to various causes such as inaccuracies of tesserae-positioning and irregular lateral expansion of the material, visually-apparent irregularities of joint width and groove shape are produced which do not necessarily occur on successive pattern-repeat areas.

21. An inlaid sheet of linoleum or the like having consolidated tesserae separated somewhat from each other and embedded in a consolidated but somewhat soft base material and standing in relief with respect to interposed and exposed portions of the base material, and having visually-apparent irregularities of joint width and groove shape which are not necessarily reproduced in successive repeat areas.

Signed at Trenton, New Jersey, this 25th day of July, 1928.

JOHN TOMEK.
